No. 710,161.

Patented Sept. 30, 1902.

F. H. LOVELESS.

BRUSH.

(Application filed Apr. 4, 1902.)

(No Model.)

UNITED STATES PATENT OFFICE.

FRED H. LOVELESS, OF LAFAYETTE, INDIANA, ASSIGNOR OF ONE-HALF TO
CHARLES L. DANIELS, OF TIFFIN, OHIO.

BRUSH.

SPECIFICATION forming part of Letters Patent No. 710,161, dated September 30, 1902.

Application filed April 4, 1902. Serial No. 101,348. (No model.)

To all whom it may concern:

Be it known that I, FRED H. LOVELESS, a citizen of the United States, residing at Lafayette, in the county of Tippecanoe and State 5 of Indiana, have invented certain new and useful Improvements in Brushes, of which the following is a specification.

The object of this invention is to provide a sweeping-brush having bunches or tufts comprising a mixture of bristles and vegetable fiber which will be cheaper than an all-bristle brush and owing to the favorable disposition of the bristles with relation to the vegetable fiber substantially as durable.

15 The object also is to provide a strong and economical means for securing the bunches to the brush-head.

I accomplish the objects of the invention by the mechanism illustrated in the accompanying drawings, in which—

20 Figure 1 is a view in front elevation and partial vertical section of my improved brush; Fig. 2, an end view of same, and Fig. 3 a diagram showing the manner of constructing the tufts.

25 Like characters of reference indicate like parts throughout the several views of the drawings.

1 represents the brush-head, preferably of wood, having an under flat side, with a series of round holes to receive the bunches. Each of these holes comprises an outer circular opening 2 and an inner concentric opening 3 of less diameter. The bunches of fiber 30 are wrapped around a short wooden core 4. This core takes into the smaller and deeper opening, while the bunch end is received in the larger and outer opening 2. In making the said bunches I rotate a rod long enough 35 for a number of bunches in a lathe, and after the bunches are formed detach them from the rod as made by sawing off the requisite length of rod. In the formation of a bunch the first operation is to kerf the rod transversely, 40 as shown at 5, and lay therein the wire 6, with its projecting end bent down toward the adjacent end of the rod. Then the body of the wire is wrapped around the rod and upon the short turned end of the wire. The proper 45 amount of bristles is then fed evenly under the wire upon the rod and the wire is con-

tinued around the half-completed bunch two or three times toward the end of the rod, and then a layer of vegetable fiber, such as is commonly used for making brushes, is laid upon 55 the bristles and the wire continued around the outside of it two or three times, as shown in Fig. 3. The end of the wire is finally secured by wrapping it around a tack or nail 7, driven through the fiber and bristles into the 60 rod. The wrapping of wire around the rod before the tack is driven therein prevents the splitting of the rod by the tack. After the wire is fastened to the tack the combined 65 layers of bristles and fiber are doubled back upon themselves and pounded to compress them. Then a ring of suitable diameter is forced on over the shoulder formed by the bent fiber and bristles to hold same in place until inserted in the brush-head, when the 70 ring is removed. After the ring is in place the rod is sawed off about a half inch from the shoulder. The head of the bunch thus completed is dipped in a germ and water proof glue and then inserted in one of the 75 double holes in the brush-head, where it is additionally retained by a small nail or brad 8, driven through the side of the brush-head into the rod above the shoulder of the bunch.

80 My object in tying a layer of bristles on the rod first and then a layer of the vegetable fiber on the bristles is to fortify the fiber by the inner core and outer layer of tough elastic bristles and to stiffen the bunch and cheapen its cost of production by introducing the intermediate layer of fiber.

Having thus fully described my invention, what I claim as new, and wish to secure by Letters Patent, is—

1. A brush-head having holes to receive the 90 bunches and bunches secured in each of said holes, each bunch comprising a core, a layer of bristles surrounding the core and wired at its middle thereto and a layer of fiber surrounding the bristles and wired thereto after 95 which both fiber and bristle layers are bent back upon themselves to form a bunch wherein said fiber is in an annular body between a center body of bristles and an outside layer of bristles.

2. In a brush, a brush-head having a series 100 of holes to receive the bunches and bunches

secured in each of said holes said bunches comprising a wooden core kerfed transversely, a wire laid in said kerf with a projecting end bent toward the end of the core and held by 5 wrapping the wire over it; a layer of bristles evenly distributed around the core and held thereto by a wrapping of wire; a layer of fiber around the bristles held by a further wrapping of the same wire and a tack driven 10 into the core to which the remaining loose end of the wire is fastened, said wire wrappings of bristles and fiber being at approxi-

mately their middles and the fiber and bristles being doubled at the wrappings to form a bunch in which an annular layer of fiber is 15 between a central body of bristles and an outside layer of bristles.

In witness whereof I have hereunto set my hand and seal, at Tiffin, Ohio, this 31st day of March, A. D. 1902.

FRED H. LOVELESS. [L. S.]
Witnesses:

HARRY TAGGART,
CHARLES L. DANIELS.
